CLAIM

The ornamental design for a side wall bracket, as shown and described.

DESCRIPTION

FIG. 1 is a perspective view of a side wall bracket for supporting pivoting bracing;

FIG. 2 is a right-side elevation view thereof;

FIG. 3 is a front elevation view thereof;

FIG. 4 is a left-side elevation view thereof;

FIG. 5 is a rear elevation view thereof;

FIG. 6 is a top plan view thereof; and,

FIG. 7 is a bottom plan view thereof.

The broken lines shown form no part of the claimed design.
